UNITED STATES PATENT OFFICE.

GUSTAVE E. VILLARET, OF NEW YORK, N. Y., ASSIGNOR TO J. H. WHITE MANUFACTURING COMPANY, OF BROOKLYN, NEW YORK, A CORPORATION OF NEW YORK.

DESIGN FOR A BODY SHELL.

Application filed November 2, 1922. Serial No. 4,210. Term of patent 3½ years.

To all whom it may concern:

Be it known that I, GUSTAVE E. VILLARET, a citizen of the United States, residing at the borough of Manhattan, city, county, and State of New York, have invented a new, original, and ornamental Design for a Body Shell, of which the following is a specification, reference being had to the accompanying drawing, forming part thereof.

The figure is an elevation of a body shell, showing my new design.

I claim:

The ornamental design for a body shell, as shown.
